UNITED STATES PATENT OFFICE.

FRANK HENNEBÖHLE, OF SOUTH CHICAGO, ILLINOIS.

AUTOMATIC DUPLEX CHECK AND STOP VALVE.

SPECIFICATION forming part of Letters Patent No. 693,133, dated February 11, 1902.

Application filed May 4, 1901. Serial No. 58,802. (No model.)

To all whom it may concern:

Be it known that I, FRANK HENNEBÖHLE, residing at South Chicago, in the county of Cook and State of Illinois, have invented a new and Improved Automatic Duplex Check and Stop Valve, of which the following is a specification.

This invention relates to improvements in that type of fluid-pressure-operated valves arranged to automatically adjust themselves under varying pressures from the supply or offtake sides, whereby to stop the feed in case the rupture is on the delivery or outlet end and cut off or check the pressure on the outlet side in case the rupture or break occurs in the feed end; and it more especially seeks to provide a very simple, inexpensive, easily-adjusted, and effectively-operating valve of the character stated more especially designed for use in the main pipe from boiler to engine, and to maintain the steam-pressure in boiler in case break or leakage is at engine, or to check steam in the main for engine in case the break is at boiler while repairs are made.

My invention in its generic nature comprehends a valve-chamber having two compartments, one of which communicates with the boiler-inlet, the other with the outlet or offtake main, the two compartments being in communication with each other, and the opening therebetween having coöperatively combined therewith a valve shiftable by the varying pressures from either side, whereby to close off communication between the inlet and outlet of the valve-casing.

Again, in its more complete nature my invention embodies a valve-casing having an inlet-compartment that joins with the boiler, an outlet-compartment, the two compartments being in communication, a single slideable valve-stem carrying a valve adapted to operate to close off either the inlet from the boiler-feed or the inlet to the offtake-main by the reduction of pressure from opposite sides, and manually-operated means for forcing the valve from the seat, to which it is held by boiler-pressure.

In its subordinate nature my invention consists in certain new features of construction and detailed combination of parts, all of which will hereinafter be fully described, and par-

ticularly pointed out in the claims, reference being had to the accompanying drawings, in which—

Figure 1 is a vertical section of an angle-valve constructed in accordance with my invention. Fig. 2 is a similar view with a slightly-modified construction of the cut-off valve devices.

In the accompanying drawings, in which like letters denote like parts in both figures, P designates the casing of the valve, which in the form shown is of the angle type. This casing has an upper and lower compartment or chamber, (indicated by A² A', respectively,) the upper one, A², of which has an outlet B, that connects with the offtake-main or engine, while the lower chamber A' has the inlet A from boiler. The upper chamber A² is also open at the top, which is closed by a cap and yoke Q, which is fastened on the ground joint S by screw-studs s, and the said cap has a stuffing box or gland N, held on the cap by the screw-studs n n, to receive the adjusting screw or spindle I, the purpose of which will presently appear, the upper end of said screw I working in a sleeve-nut R, held on the yoke Q, and its upper end carries a hand-wheel K, and at its lower end it carries a head M to engage the seat m on the under face of the cap, as clearly shown in the drawings.

The chamber A' has a supplemental pendent portion a, in which is disposed a spider-frame D', having an annular member having a valve-seat D threaded into an annular threaded rim a' in the bottom of chamber A' proper and a central bearing d to receive the lower end of the vertically-slid valve-stem F.

C' designates a second spider-frame detachably held in the opening a^X between the two chambers, and in the form shown in Fig. 1 this frame C' has an annular valve-seat C on its under side, which opposes the seat D below it, and a central guide-bearing c to receive the upper end of stem F.

E designates a double-faced valve-disk mounted on the stem F, and within chamber A' said disk has bevel-seats e e' on the upper and lower faces, adapted to coöperate with the beveled seats C and D, respectively, of the casing in a manner presently explained.

H is a coiled spring disposed about the stem F between the disk E and bearing c, and has for its object to hold the valve-disk E down toward the boiler-pressure. G designates a light coiled spring, which has for its purpose to hold the weight of the valve-disk slightly up from its seat to prevent the hammering or clinking of the valve against the seat by the pulsation of steam.

10 So far as described the manner in which my construction of valve operates is explained as follows: When it is desired to cut off the boiler-pressure, the screw-spindle I is turned down to push the stem F down to

15 bring the valve-disk E, with its under bevel e', solid against the valve-seat D, as shown in dotted lines in Fig. 1. To open the valve, the screw I is raised full open until its head M is solid against its seat, as shown in full

20 lines in Fig. 1. The boiler-pressure (if in excess of the pressure in steam-main) will lift valve-disk E up, as shown, pass up into chamber A', into chamber A², and out through discharge B into the offtake or steam main, it being understood that during this operation the spring H tends to hold the disk E down against the pressure and toward its seat D, and in practice the said spring H is made sufficiently strong to allow for slight

25 variation of the steam in main and allow said valve-disk E to move up and close against the upper seat C only at a certain or predetermined drop of steam-pressure in the main below the boiler-pressure. Thus should a

30 rupture or break occur in the main and the pressure in the main be sufficiently lower than boiler-pressure to counterbalance the back pressure of the spring H the boiler-pressure will move disk E up and hold it

35 lightly against the seat C, and in consequence cut off the boiler from engine or steam-main during repairs. To again set valve into an operative condition after the repairs are made to engine or main, it is only necessary to

40 screw down the spindle I, the head M of which in engaging stem F will force the valve-disk E down from the seat C, from which it will be held by the steam-pressure above it when the pressure in the valve from the boiler

45 balances in the valve-casing. Should a rupture or break occur in the boiler and the pressure from boiler fall below that of the pressure on the main, the disk E will be instantly shifted to close down against the seat

50 D, and thus close off the main and engine from boiler pending repairs, it being obvious that when pressure in boiler is restored above that of pressure in main back of disk E said restored boiler-pressure will again lift

55 the disk E from seat D.

Under some conditions it is desirable to use two valve-disks on the stem F, as shown in the modified construction illustrated in Fig. 2, in which L designates the second disk 60 mounted on the upper end of the stem F and movable within the chamber A². In this lat-

ter form the member C' has a seat c^x on its upper face to receive the impacting-surface L' of the disk L, which is held on the stem by the nut l, as shown.

In the form shown in Fig. 2 when the boiler-pressure is reduced below that of pressure in the main the disk L closes down onto the seat c^x as the disk E closes down on seat D.

It will thus be seen that valve E prevents steam getting out of boiler when the break occurs in main, and by reason of the manner in which it and the stem F is held the action of the valve is entirely automatic for promptly closing in whatever direction the steam diminishes in pressure to a certain point below that for which the spring H is inserted—i. e., should the rupture occur in boiler the stem F, with valves, will descend, and if break or serious leak happens to steam-pipe the stem, 85 with valve, ascends.

By using two disks on the stem F, as shown in Fig. 2, my improvements are also suitable for horizontal pipes by putting the inlet A opposite outlet B and to discharge into chamber A', which in such case would be closed at bottom and have the shape of an ordinary globe-valve.

Slight changes in the details of construction and further modifications of the parts 95 may be made without departing from the scope of the appended claims. For example, a wing-style valve may be substituted for the disk on the stem F.

Having thus described my invention, what I claim, and desire to secure by Letters Patent, is—

1. A valve, comprising a casing having an inlet for connecting with the boiler, an outlet for joining with the main or feed pipe, a valve-chamber joining the inlet and outlet portions, said chamber having a valve-seat communicating with the outlet, and a valve-seat communicating with the inlet, a valve shiftably held within said chamber adapted to automatically close onto either of said seats by the varying fluid-pressure against it in either direction, for the purposes specified.

2. A valve, comprising two communicating chambers A' A², the opening therebetween having a valve-seat, the chamber A², having a laterally-projecting outlet for connecting with the main, the chamber A' having a valve-seat adjacent its inlet or boiler-connecting end, a valve held within the chamber A', away from either valve-seat by the balanced fluid-pressure on its opposite sides and adapted to shift to engage either seat by the varying pressure on either side, as specified.

3. A valve comprising a casing, having two communicating chambers, one of which has an inlet, the other an outlet, a valve shiftably held within the inlet-chamber, adapted to alternately close the inlet to said chamber, or the opening between it and the outlet-chamber, to be held up against the said opening by boiler-pressure, and manually-operated

means for forcing said valve away from the said outlet-opening, and against its boiler-pressure, for the purposes described.

4. The combination with the casing, having an inlet-chamber and an outlet-chamber, the two chambers communicating, a shiftable stem, having attached means for alternately closing off the inlet-chamber to the outlet-chamber or to the boiler, by the varying fluid pressures from opposite directions, said stem and its attached closure means being spring-pressed in the direction of the inlet to the valve-casing, as set forth.

5. The combination with the casing, having an inlet-chamber A', an outlet-chamber A², an opening joining the two chambers, having a valve-seat, a stem slidably mounted within the casing having attached closure means for engaging the valve-seat, a spring for forcing the stem and its closure member normally in the direction of the inlet end of the casing, and a second spring for holding said closure member off the entrance to the inlet-cham-

ber, all being arranged substantially as shown and described.

6. The herein-described improvements in valves, comprising the following elements in combination, a casing having an inlet-chamber A' and an outlet-chamber A², in communication with each other, the skeleton frames C' D', having the valve-seats C and D, and central guide members c and d, the cap and yoke, detachably mounted over the chamber A², the screw-spindle I, carried by the yoke and cap, and adjustable within the upper or outlet chamber A², the stem F, slidably mounted in the guides c and d, the disk E, mounted on the stem F, and having its upper and lower faces fitted to engage the seats D and C, the spring H, and the spring G, all being arranged substantially as shown and for the purposes described.

FRANK HENNEBÖHLE.
